UNITED STATES PATENT OFFICE.

PAUL R. HAY, OF PITTSBURGH, PENNSYLVANIA.

DISPLAY DEVICE.

1,283,751.

Specification of Letters Patent.

Patented Nov. 5, 1918.

Application filed July 6, 1916. Serial No. 107,785.

To all whom it may concern:

Be it known that I, PAUL R. HAY, a citizen of the United States, and a resident of Pittsburgh, North Side, in the county of 5 Allegheny and State of Pennsylvania, have invented a new and useful Improvement in Display Devices; and I do hereby declare the following to be a full, clear, and exact description thereof.

10 My invention pertains to display devices, and relates especially to electrically-lighted signs of the character in which the light varies and changes for the purpose of attracting attention thereto. In electrically-lighted signs of this general character, it is common to provide means for intermittently switching the light on and off, to produce a flashing effect; it is common, further, to provide rotating casings having glasses therein 15 of different colors, whereby a changing striped effect is obtained; and it is common, also, to provide, within a suitable shade or translucent covering, a plurality of lamps of different colors, cooperating with a 20 switching device, which switches on one of the lamps at a time, thus effecting a changing-color lighting effect. In all of these devices, however, the changes are regular—*i. e.* if a light is simply switched on and off, the 25 effect takes place at definite intervals; if a rotating cage having glasses of different colors is employed, the different colors come up at regular intervals; if a plurality of different colored lamps are switched on in succession, the different colors show at uniform 30 periods. In all these devices there is a monotonous regularity, which does not tend toward the device forcing itself upon the public attention, as is desired.

35 It is the object of this invention to provide an electrically-lighted device which will present constantly varying colors which come up in no fixed order of succession, and in which colors of all kinds—including the 40 solid colors, striped effects, and variegated effects—are presented.

I attain this object by providing, within a suitable translucent covering, such as a frosted globe, a plurality of "skeedoodle 45 plugs". A skeedoodle plug is a device formed at one end with a plug for entering a lamp socket, and formed at the other end with a socket for receiving a lamp base, which device contains a resistance coil and 50 contact means, so arranged and constructed

that when the lamp is glowing, the resistance coil becomes heated and thereby increases in conductivity, which results in the circuit being broken, whereupon the lamp goes out. When the lamp is out, the coil 60 cools and, in due time, establishes the contact, whereupon the lamp begins to glow again. Thus the use of the skeedoodle plug results in the lamp alternately glowing and 65 going out. These skeedoodle plugs are well known in the art under that name, and are largely used, in their individual relation, in electrical display devices. In obtaining the results sought after, I provide a plurality of 70 these skeedoodle plugs, arranged in cluster form, with a lamp of different color in each. The cluster of lamps is surrounded by a translucent covering, such as a frosted globe or the like. A skeedoodle plug does not effect the switching on and off of the light at 75 accurately divided intervals; and, in any case, the skeedoodle plugs on the market are provided with adjusting means which permits their periods to be varied. Thus the lights within the globe will be irregular as 80 to which of them will be going at one time. Considering the lights as being red, blue and yellow, which are the three primary colors, the red lamp may be glowing alone, it may be glowing in conjunction with the blue 85 lamp, it may be glowing in conjunction with the yellow lamp, or it may be glowing in conjunction with both the blue and the yellow lamps; and, during the glowing of the red lamp, either the blue lamp 90 or the yellow lamp may go on or off. It is obvious that, when the cluster is surrounded by a translucent globe or the like, the result is a continuously varying exhibition 95 of shades of color, which do not recur at any fixed intervals. Sometimes solid colors will be produced; sometimes the colors will appear in stripes; and sometimes variegated colors will be presented. The display device thus produced is far more attention-demanding than is the case with the regularly recurring devices at present on the market.

By way of an example of one construction in which my invention may be embodied, I have shown in the accompanying 105 drawing, and described below, one form of display device constructed in accordance therewith. I wish it understood, however, that the invention may be embodied in other forms, and that changes may be embodied 110

in the form described and shown, without exceeding the scope of the invention, as defined in the appended claim.

In the drawings:

5 Figure 1 is a side elevation of a display device constructed in accordance with my invention, part of the globe broken away to disclose the skeedoodle plugs and lamps.

10 Figs. 2 and 3 are sectional views of one of the skeedoodle plugs, taken at right angles to each other, to clearly illustrate the interior mechanism of such plugs.

15 Referring now to the drawing, 10 indicates a suitable hood or the like, to which conductors are brought, through a conduit 11. Suitably supported within the hood 10, are three lamp sockets 12, disposed in the usual parallel relation and arranged in cluster form. In the lamp sockets are inserted 20 skeedoodle plugs 13, 14 and 15, each of which is provided with a lever 16 for adjusting the length of the period at which the lamp carried by the particular skeedoodle plug shall remain glowing. The 25 skeedoodle plugs 13, 14 and 15 carry lamps 17, 18 and 19, of which the lamp 17 may be red, the lamp 18 may be yellow, and the lamp 19 may be blue.

30 These being the three primary colors, they will, by being combined together in different ways, produce all the other colors.

35 The hood 10 is provided with the shade holder 20, in which is supported, in the usual manner, a translucent globe 21. The globe 21 has its surface decorated with any desired advertising legend, such as 22.

40 The skeedoodle plugs 13, 14 and 15 comprise a casing 23 in which is secured a disk of insulating material 24, for supporting thereon a thermostatic member comprising coils 25. An adjustable contact member 16 is mounted on one of the coils 25 and adapted to be adjusted to or from a permanent contact 26 on the other coil. The upper 45 end of the casing 23 is closed by an insulating member 27 supporting a contact 28, having a lead wire 28' extending therefrom and secured to one of said coils 25. The lower end of the casing 23 is screw-threaded 50 to form a socket portion and is surrounded on the outside by an insulating casing 29. A contact member 30 is supported on the underside of the disk 24 and is in circuit with one of the coils 25.

55 The operation of the above device will be readily understood without describing it

in detail, since it is a well known form and operation of thermostatic construction, the circuit being made and broken through the contacts 16 and 26 due to the effect of the 60 current on the coils 25.

When current is first switched on to the device, the three colors may start to glow fairly closely together, unless one or more of the adjusting devices 16 have been 65 operated to prevent this; but, after the device has been in operation for a little time, the irregularity of the periods of change of the three skeedoodle plugs, will cause the colors to come up at different times and in 70 constantly varying combinations, as has been described above.

The device described has the advantage of the continuously changing, and beautifully colored, lighting effects it presents, 75 which lighting effects are of a nature peculiarly adapted to command the attention, and thus display the advertising legend in great prominence. It has the further advantage that, by the use of only three lamps 80 (and these not in operation all the time), it will produce an innumerable number of successive colors. Of course, a cluster comprising a different number of skeedoodle plugs and lamps may be employed without 85 exceeding the scope of my invention, as defined in the claim. The lamps must however, be disposed in cluster form, since otherwise they would be liable merely to present their individual colors to the eye. 90

Having thus fully described my invention, what I claim as new and desire to secure by Letters Patent is:—

95 In a display device, a cluster of three electric bulbs, sockets for said bulbs, each of said bulbs being of a different primary color, said cluster being so arranged that one of said bulbs partly overlaps the other two, an individual current-controlled device carried by each of said sockets and associated 100 with each bulb for causing the current to be intermittently supplied thereto and off therefrom, and a translucent cover inclosing and surrounding said cluster of bulbs, for 105 the purpose set forth.

110 In testimony whereof, I the said PAUL R. HAY have hereunto set my hand.

PAUL R. HAY.
